UNITED STATES PATENT OFFICE

161,691

DOLL

Thelma E. Holford, Jonesboro, Ark.

Application February 13, 1950, Serial No. 7,913

Term of patent 14 years

(Cl. D34—4)

To all whom it may concern:

Be it known that I, Thelma E. Holford, a citizen of the United States, residing at Jonesboro, in the county of Craighead and State of Arkansas, have invented a new, original, and ornamental Design for a Doll, of which the following is a specification, reference being had to the accompanying drawing, forming part thereof.

Figure 1 is a front perspective view of a doll showing my new design, and

Figure 2 is a rear perspective view thereof.

Figure 3 is a fragmentary view showing a profile view of the head of the doll with part of the brim of the hat broken away for convenience of illustration.

I claim:

The ornamental design for a doll, as shown.
THELMA E. HOLFORD.
